FOOT PEDAL

Jesse D. Langdon, Downey, Calif., and John J. Delany, Brooklyn, N. Y.

Application January 22, 1942, Serial No. 427,712

4 Claims. (Cl. 74—512)

The invention relates to foot pedals for operating valves or the like.

More particularly, the invention relates to foot pedals located at or near the floor.

An object of the invention is to provide a foot pedal capable of an oscillating movement, which is of simple construction and reliable in operation, and when pressed by the foot of the operator recedes from the direction of applied pressure, regardless of the angle or direction of the applied pressure.

An object of the invention is to provide a foot pedal which eliminates the possibility of the operator standing upon the same, effected by a coniform pedal element which is engaged by the foot of the operator and mounting the same to impart thereto an oscillating motion.

A further object is to provide a coniform foot pedal of suitable proportions wherein the base thereof is extended radially outward from a central stem forming a longitudinal axis with relation to a mounting base and projecting toward the apex of the cone; said cone having a sufficient base diameter to cause the same to easily rotate about the axial line formed by the stem which is oscillatably mounted with a conjoining retaining base to permit relative universal movement between the cone and stem, whereby the foot of an operator attempting to stand thereon will be deflected therefrom particularly as the mounting is provided with means to allow the pedal to recede from any source of pressure exerted against the external surface of the cone.

Further features and objects of the invention will be understood from the following detail description and the accompanying drawing, in which

Fig. 1 is a vertical, central, sectional view of one preferred embodiment of the invention;

Fig. 2 is a vertical, central, sectional view of another preferred embodiment of the invention.

Referring to the embodiment illustrated in Fig. 1, the pedal element 10 is, as shown, of coniform formation, which may be, and preferably is, hollow; the pedal element may be of metal, cast or otherwise fabricated. The stem 11 is suitably secured to the pedal element 10, as by screw-threaded connection 11a, as shown.

Secured to the other end of the stem 11 is a button-like element 12, located for universal movement within the cowl 13, the latter having an opening 13a which may be circular, and of a diameter less than the diameter of the button-like element 12.

The cowl 13 is suitably supported in the posi-

tion indicated in Fig. 1 by any suitable means, not shown.

The assembly comprising the mechanism shown includes a mounting base comprising a ring element 17 upon which rests a compression spring 16 surrounding a stem 15. The stem projects thru the spring and forming a plunger having a flange 14 which impinges the curved face of the flange 12 formed on the proximal end of oscillatable stem 11. The stem is retained in operative position by the internal flange of sleeve 13 which provides the opening 13a to permit universal movement of stem 11 on the distal end of which is mounted the coniform pedal 10. The cone 10 should be mounted to permit not more than the apex to contact floor 21.

When pressure is exerted against the external surface of cone 10 it is caused to recede away from the direction of exerted pressure and is free to recede against the spring 16, turn on a horizontal axis, a transverse axis, or oscillate as the case may be according to the directional stress.

It will therefore be seen that it is entirely impossible to hold the foot pedal in a fixed position where pressure is exerted by any object of a nature which cannot grasp and hold the cone against rotative or receding movement. The foot pedal and any valve to which it may be attached is thereby protected against abuse by standing thereon.

The shoe of the operator indicated at 20 in Fig. 1, illustrates an initial stage of application of pressure, the pedal element 10 in its normal position being shown in full outline. Upon application of pressure by the foot of the operator pressed upon the pedal element 10, the pedal element is lowered and rotated, say, to its dot-and-dash outline position 10' and its stem 11 to its dot-and-dash outline position 11', whereupon the button-like element 12 is moved to its dot-and-dash operated position 12' and the head 14 of the valve operating plunger 15 displaced to its dot-and-dash operated position 14'. In such downward rotational movement of the pedal element 10, the heel of the foot of the operator pivoting from a fixed pivot point in contact with the floor, indicated at 21, less and less area of contact ensues between the sole of the foot of the operator with respect to the coniform configuration of the pedal element 10 until the pedal element engages a fixed object, in this instance the floor indicated at 21. Thus, the pedal element 10 and its stem 11 are protected against breakage.

The coniform shape of the pedal element and

its path of movement, accordingly, defeats any attempt of the operator to "stand" on the pedal element, and in fact facilitates release by the operator of the foot pedal assembly with minimum effort and concentration; and as shown in Fig. 1, the disposition of the pedal element above the floor and the angle of conicity thereof is such that the large area of contact of the pedal with the floor protects the pedal and stem against breakage. The foot-contacting surface of the pedal assumes a large angle with respect to the floor which prevents the operator from exerting a strong effective pressure against the pedal, affording additional protection thereof.

In the embodiment shown in Fig. 2, like parts as compared with the embodiment of Fig. 1 are indicated by like reference characters. The embodiment shown in Fig. 2 illustrates in particular the mounting of the stem 11 by means of a universal joint connection, indicated generally 22, such as comprising a ball 11b and a casing 24 having an opening through which the stem 11 extends, which opening has a predetermined diameter for positively limiting the maximum arc of oscillating movement of the pedal element 10 and its stem 11, as appears from the dot-and-dash outlines of these parts, indicated in Fig. 2.

Fig. 2 illustrates also suitable means such as a bracket 25 or the like for supporting the housing 13, enclosing the valve operating plunger 15 and its head 14, guided within the housing 13. A face plate 26 having an opening 26a is also shown in Fig. 2 for mounting the button-like element 12 within the housing 13. The expansile spring 27 in this instance is shown of conical outline and abutting the inner face of the hollow coniform pedal element 10 and a face of the button-like element 12. The plunger rod 15, also, is shown actuating a bell-crank 28, having a return spring 28a, and operating a shaft 29, or the like.

The advantages gained by the employment of the coniform pedal element 10 in the arrangement illustrated in Fig. 2 are of like nature as are attained in the arrangement illustrated in Fig. 1. In the arrangement of Fig. 2 there are additional advantages, namely, that the pedal element 10 affords restricted axial turning about its stem 11 and partial bodily rotation of the pedal element 10, itself, with respect to its stem 11, restricted by the spring 27. The arrangement illustrated in Fig. 2 possesses the further advantage that the fixed object against which the pedal element may be brought to its final position, is a bracket or equivalent serving also for maintaining thereon the housing 13 of the operating mechanism.

From the above, it appears that our invention affords foot-pedalling means comprising in com-

bination a pedal element of rigid coniform formation, adapted to be engaged by the foot of the operator and when in normal position disposed in a plane at an angle to the horizontal and vertical, said rigid conical pedal element being mounted either fixedly or resiliently and articulatedly upon a stem, such stem normally extending horizontally, means operated by such foot-pedal means, a reciprocated element arranged to actuate or set into actuation such operated means, means in operative relation with said reciprocated element for locating said pedal element in normal position and means for mounting such pedal element to impart thereto a combined rotary and bodily displacement movement.

Whereas we have described our invention by reference to specific forms thereof, it will be understood that many changes and modifications may be made without departing from the spirit of the invention.

We claim:

1. A pedal assembly of the kind described comprising a support, a flanged plunger resiliently and horizontally mounted in said support, a flanged stem in contact with the plunger and universally mounted relative to said support and plunger, the distal end of said stem surmounted by a coniform foot pedal having a sufficiently steep surface with relation to the plane of the stem axis and a sufficient base diameter extending radially outward of said stem to provide such leverage and to present the required external face angularity for the cone with relation to said stem to permit of easy rotation of said cone about the axial line formed by said stem, whereby the pedal will recede away from the direction of continued pressure and turn about the axial line formed by the stem.

2. In combination, a support, a stem longitudinally and horizontally mounted with relation to said support, said support including means for universally mounting the stem of a pedal; a cone mounted on the distal end of the last mentioned stem, the base of the cone facing the mounting means and having an outer face sufficiently steep with relation to the axial line of the last mentioned stem whereby the foot of an operator attempting to stand on the cone will be deflected therefrom.

3. A foot pedal as of claim 2 wherein the cone is mounted on the distal end of the stem by a universal joint.

4. A foot pedal as of claim 2 wherein the cone has a hollow base and is internally attached adjacent the apex of the cone.
